UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,893, dated November 14, 1893.

Application filed October 7, 1893. Serial No. 487,514. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental scrolls forming a series of panels having vase-like ornaments in the center of said panels filled with flowers and leaves as represented in the accompanying drawing. The border or upper portion of the said design is formed of said vase-like ornaments filled with flowers 10 and leaves and ornamental scrolls between said ornaments connecting the flowers and leaves springing from said vase-like ornaments. Small fleur-de-lis shaped ornaments connected by semi-circular curved lines and intersected by a horizontal line form the base 20 or lower portion of the border of said design as shown in the drawing.

What I claim is—

1. The design for wall paper herein shown and described.
2. In the design for wall paper the border herein shown and described.

Witness my hand this 2d day of October, 1893.

CHARLES BOOZE.
